UNITED STATES PATENT OFFICE.

FRANK W. SCHUMACHER, OF SHAWANO, WISCONSIN.

WIRE-STRETCHER.

1,313,339.

Specification of Letters Patent.

Patented Aug. 19, 1919.

Application filed April 10, 1919. Serial No. 288,960.

To all whom it may concern:

Be it known that I, FRANK W. SCHUMACHER, a citizen of the United States, residing at Shawano, in the county of Shawano and State of Wisconsin, have invented 5 certain new and useful Improvements in Wire-Stretchers, of which the following is a specification.

This invention relates to pushing and 10 pulling implements, and more especially to stretchers operating on the step by step principle; and one object of the same is to produce an improved fence-wire stretcher which is capable of use between posts within the 15 run of the fence, or beyond the endmost post when the operator reaches the end of said run.

Another object is to produce a structure 20 which grips the wire at two points, one on either side of the post, so that the wire can be stapled to the post after it is stretched.

Another object is to provide a detachable shoe which is not applied when stretching is done between posts.

25 Other objects will appear in the following specification and claims.

In the drawings:—

Figure 1 is a plan view of this wire stretcher with its parts assembled as when 30 it is attached to the end post, and

Fig. 2 is a side elevation thereof.

Fig. 3 is an enlarged plan view of the movable slide and pawls.

In the drawings the numeral 1 designates 35 the ordinary bar having staggered notches 2 in its sides and herein shown as provided at one end with a hook 2' which may be attached to a post and a chain 3 with a grip 3' to be attached to the wire when the wire 40 is to be stretched within the run of the fence. The other end of the bar 1 is provided with a tongue 4 adapted to be slipped into a socket 5 which carries a shoe 6 preferably having points 7 whereby it may rest 45 against a post P when the wire W is to be stretched at the end of a run of fence, or in other words when the stretcher is to be employed beyond the line of the fence itself. In this case, the chain 3 cannot be attached 50 to the fence post because there is no such post, and it may well be led over along the dotted line of Fig. 2 and attached to the upper end of the post P to hold the notched bar 1 horizontal. The shoe 6 may be attached to the post P in any suitable manner, 55 as by a clamping chain 8 carried around the

same and engaged with a hook 9 on the shoe. It is to be understood that this shoe and socket are not employed when the stretcher is used within the length of the fence. 60

Slidably mounted on the notched bar is a hollow member or slide 10 best seen in Fig. 3, and pivoted at 11 across the same is a lever 12 to which at 13 are pivoted pawls 14 whose active ends are thrown normally inward by springs 15 engaging the sides of the slide as seen in Fig. 1. Therefore, when the lever is reciprocated, the pawls cause the slide to travel to the left along the notched bar in a manner which will be clear. 70

A pulley 22 is pivoted on the slide 10 as at 21, and the pins 11 and 21 connected by a bracing link 16. Around this pulley passes a chain 23 having grips 24 and 25 at its extremities which are adapted to be engaged with the fence wire W at opposite sides of the post P, the grip 24 being considerably nearer the stretching mechanism than the grip 25. In other words, the last-named grip is within the line of the fencing, while the grip 24 is beyond the post P which is here the left post of said line. The chain 23 which connects the grips passes the post from the grip 25 and runs freely around the pulley 22, but it is quite possible to provide means for preventing the rotation of said pulley when desired. The grip 24 carries a hook 26 and the chain 23 has a large link 27 adjacent the grip 25. 80

When this stretcher is used within the line 90 of the fence, the hook 2' is attached to a post and the grips 24 and 25 to a wire to be stretched, or the grip 25 can be attached to the wire and the hook 26 on the grip 24 may be engaged with the large link 27 on the grip 25. Then by manipulating the lever, the slide 10 is caused to move to the left and the wire is stretched as clearly understood. When this device is to be used at the end 95 of a stretch of fence, the shoe 6 is brought into use and the socket 5 is slipped over the tongue 4 at the right end of the notched bar 1, the toothed inner face of the shoe being applied to the post as seen, and the clamp 8 fastened to hold it in place. It is possible now that the chain 3 may be brought over to the position shown in dotted lines in Fig. 2, and wrapped around the upper end of the post P to hold the bar horizontal. The fence wire W being led alongside the post and the two grips 24 and 25 applied to it about 105 as indicated in Fig. 1, when now the lever 110

12 is reciprocated, the pawls cause it to travel to the left along the notched bar and the pulley 22 strains both stretches of the chain 23. The result is that the grip 25 10 draws on the main portion of the wire W while the grip 24 draws on that portion of the wire between the two grips, which portion extends alongside the post, and therefore the wire may be stapled thereto before tension on the structure is relaxed. Now a reversal of the operation removes the stretcher and it is possible to reset it at a lower point on the post so as to stretch the wire W below. The parts are by preference 15 entirely of metal, and changes in detail may be made as come within the scope of the invention.

The foregoing description and the drawings have reference to what may be considered the preferred, or approved form of my invention. It is to be understood that I may make such changes in construction and arrangement and combination of parts, materials, dimensions, et cetera, as may prove 20 expedient and fall within the scope of the appended claims.

What is claimed as new is:—

1. In a fence wire stretcher, the combination with a bar, a slide movably mounted 30 thereon, means for causing its progression along the bar, and means for attaching said bar to a fence post; of a pulley on the slide, a chain led over said pulley, and grips at opposite ends of said chain for attachment 35 to the fence wire.

2. In a fence wire stretcher, the combination with a bar, a slide movably mounted thereon, means for causing its progression along the bar, and means at opposite ends of 40 said bar for selective use in attaching it to a fence post; of a pulley mounted on said slide, a chain passing around said pulley and with one stretch adapted to be led past a fence post, and grips at the extremities of 45 said chain for attachment to the fence wire at two points, as described.

3. In a fence wire stretcher, the combination with a notched bar, and means at one end thereof for attaching it to a fixed ob-

ject; of a tubular slide movably mounted on 50 said bar, pins upstanding from the slide, a lever pivotally mounted on one pin, a pawl carried by one end of the lever and adapted to engage the notches of the bar, a pulley 55 mounted on the other pin, a link connecting the upper ends of the pins, a chain passing around said pulley, and means on the chain for engaging the fence wire.

4. In a fence wire stretcher, the combination with a bar, means for attaching it to a 60 fixed support, a slide movably mounted on said bar, manually operable means for adjusting the slide along the bar, and a pulley on the slide; of a chain passing around the pulley, grips at the extremities of the chain, 65 the latter having a large link adjacent one grip, and a hook on the other grip adapted to be engaged with said large link, for the purpose set forth.

5. In a fence wire stretcher, the combination of a bar, a slide movably mounted thereon, means for causing its progression along the bar, and means for attaching it to a fence post, of a pulley mounted on said slide, a chain passing around said pulley and with 70 one stretch adapted to be led past a fence post, and grips at the extremities of said chain for attachment to a fence wire at two 75 points, as described.

6. In a fence wire stretcher, the combination with a bar, and means for attaching it to a fixed object, of a slide movably mounted on said bar, pins upstanding from the slide, of a lever pivotally mounted on one pin, means carried by said lever to engage the 80 bar and move the slide along the bar as the lever is swung, a pulley mounted on the pin, a link connecting the upper ends of said pins, a chain passing around said pulley, and means on the pins for engaging the fence 85 wire.

In testimony whereof I affix my signature in presence of two witnesses.

FRANK W. SCHUMACHER.
